(57) **CLAIM**

The ornamental design for a dispenser for stick form solid edible foods, as shown and described.

DESCRIPTION

FIG. 1 is a front elevation view of the design of a dispenser for stick form solid edible foods.

FIG. 2 is a rear elevation view of the design of a dispenser for stick form solid edible foods of FIG. 1.

FIG. 3 is a side elevation view of the design of a dispenser for stick form solid edible foods of FIG. 1, wherein the opposite side elevation view is a mirror image.

FIG. 4 is a bottom plan view of the design of a dispenser for stick form solid edible foods of FIG. 1.

FIG. 5 is a top plan view of the design of a dispenser for stick form solid edible foods of FIG. 1.

FIG. 6 is a left frontal vertical perspective of the design of a dispenser for stick form solid edible foods of FIG. 1 shown in a storage position; and,

FIG. 7 is a substantially horizontal frontal perspective of the design of a dispenser for stick form solid edible foods of FIG. 1 showing a ribbon of solid food being dispensed therefrom.

The portions of the drawing in FIG. 7 shown in dashed lines form no part of the design of this invention.
